UNITED STATES PATENT OFFICE.

RUSH W. CARRINGTON, OF KANSAS CITY, MISSOURI.

HINGE FOR WINDOW-SCREENS.

No. 882,813.

Specification of Letters Patent. Patented March 24, 1908.

Application filed May 27, 1907. Serial No. 375,993.

To all whom it may concern:

Be it known that I, RUSH W. CARRINGTON, a citizen of the United States of America, residing at Kansas City, in the county of Jackson and State of Missouri, have invented certain new and useful Improvements in Hinges for Window-Screens; and I do hereby declare that the following is a full, clear, and exact description of the invention, such as will enable others to make and use the same, reference being had to the accompanying drawings, forming a part of this specification.

The object of the invention is a hinge for full size screens to windows, the parts of which are inexpensive and quickly applied and in which a convenient adjustment is afforded in applying the parts to the screen and window.

The invention consists in the novel construction and combination of parts, such as will be first fully described and then specifically pointed out in the claims.

In the drawings: Figure 1 is a front view in elevation of the upper portion of a window frame, and of a window screen, showing the hinge applied thereto. Fig. 2 is a vertical sectional view of the window frame and screen taken upon the line x, x , on Fig. 1. Fig. 3 is an enlarged vertical sectional view 30 of the window pane taken upon the line y, y , on Fig. 1. Figs. 4 and 5 are side and perspective views in detail of the members or parts of the hinge. Fig. 6 is a view in perspective, showing the parts of the hinge, and also showing portions of the top board of the window frame and top rail of the screen, with which the parts of the hinge are connected. Figs. 7 and 8 are sectional and front views, respectively, of a brick mold and the top of 40 the screen, showing the hinge connected with the brick mold. Fig. 9 is a modification of one of the parts of the hinge.

Similar numerals of reference indicate corresponding parts in all the figures of the drawing.

Referring to the drawing, 14 indicates one member or part of the hinge which is made from wire, the main stem, 16, being straight and provided with a screw thread 17 at one 50 end, a portion of the other end of the stem being bent at right angles to form an arm, 18. The other member, 19, consists of a main stem, 20, of the desired length, one end of which stem is bent at right angles to the 55 stem to form an arm, 21, and the other end bent at right angles to the stem 20, and also

at right angles to the arm 21, and is screw threaded at 22 to form a shank for attachment to the window screen, the arms 21, in a pair of the members 19 extending in opposite directions. 60

In applying the hinge, the screen, 25, is set within the window frame against the blind stops, as seen in Fig. 1. At points a short distance above the lower edge of the face board, 23, at the top of the window frame and at equal distances inwardly from the ends of said face board are inserted the screw threaded ends, 17, of the member 14, the screw threaded end 17 being turned by the hand or a bit stock, which latter is preferable, until the arms 18 approach the face board to within a short distance. The screw threaded ends 22 of the other member 19 of the hinge is inserted in the top rail, 26, of the window-screen and at a point on the inner side of vertical lines extending through the arms 18, the arms, 21, of a pair extending, as before stated, in opposite directions. 65

The upper portion of the window screen is drawn outwardly a short distance and the stem 20 of each portion 19 of the hinge rotated, forcing the threaded portions 22 into the top rail 26 to a position in which the stem 20 approaches quite closely the said 70 rail. The upper portion of the window screw is now replaced within the window frame and a partial rotation given to the stem 20, which causes the arms 21 to hook over or engage with the arms 18, on the other portion 14 of the hinge, the stem 20 being quickly connected with the window screen and the arms 21 adjusted either in close contact with the arm 18, or a short distance away from said arm, as found desirable, the 75 slight inward adjustments of the arm 18 effecting a contact of the top rail 26 of the window screen with the lower surface of the face board 23 as close as desired, so as to bind, if preferred, it being obvious that the 80 change of position of the stem 20, lengthens or shortens the distance from the arm 18 on the stem 16, of one part of the hinge to the screw-threaded portion 22, of the part 19 of the hinge. The staple 13 is then driven into 85 the top rail 26 of the window screen, the prongs passing the sides of stem 20 and securing said stem from accidental removal. Instead of employing the staple 13, a spud may be employed on the side of the stem toward the top rail of the window screen, 90 which is quite thin and provided with a

sharp edge, so as to be driven into the top rail, as seen in Fig. 9. In this construction the portion 29 of the hinge is smooth and tapered to a point, so as to be driven into the top-rail, the prong and spud affording a capability of rapid attachment of said part of the hinge to the top rail. When the hinge is applied to window frames in which the window screen fits within a brick molding, the threaded portion, 17, of the part 14 of the hinge is inserted upwardly into the brick molding, 28, as seen in Figs. 7 and 8. The other part of the hinge is attached to the window screen as before described, and the upper portion of the stem 20 bent outwardly a short distance so as to permit the window screen to fit within the brick molding, the parts of the hinge engaging as before described.

The window screens of the above description are usually confined within the window frame and when necessary to open the screen are swung outwardly from the bottom. 20

Having fully described my invention, what I now claim as new and desire to secure by 25 Letters Patent is:

A hinge for window screens, comprising a screw threaded shank adapted to be secured to the window screen, and a stem on said shank and an arm on said stem, forming an 30 L shaped head lying in a plane in which each arm of said head is at right angles to said shank, the outer end of which is adapted to engage a second screw member.

RUSH W. CARRINGTON.
